COCKING MECHANISM FOR BOLT ACTION RIFLES

Joseph Henry Barnett, Birmingham, England, assignor to J. H. Barnett, Son and Company Limited, Birmingham, England, a company of Great Britain

Application March 4, 1947, Serial No. 732,283
In Great Britain March 12, 1946

4 Claims. (Cl. 42—16)

1

This invention has reference to improvements relating to rifles and has for its object to provide a simple bolt action mechanism for rifles which makes for comfort in use and ease of operation.

According to the invention the improved bolt action mechanism for rifles is characterised in that the movement of the bolt for loading and extraction operations is effected by a cocking lever which is mounted on the underside of the rifle and which is associated as a unit with a tumbler-lever the tumbler-lever effecting a cocking of the firing mechanism when the said cocking lever is operated for this purpose preparatory to loading.

According to the invention also the improved bolt action mechanism for rifles is characterised in that the movement of the bolt to permit loading and for extraction is effected by a cocking lever which is mounted on the underside of the rifle and in that the bolt and the lever are provided with complementary surfaces which co-act to provide a wedging action for effecting a positive locking of the bolt when the said bolt is in the breech closing position.

The invention also resides in a bolt action mechanism for rifles constructed, arranged and adapted for use substantially as will be described hereinafter.

An embodiment of the invention will now be described with particular reference to the accompanying drawings which illustrate the invention in an embodiment which is especially suitable for a small bore rifle intended primarily for match shooting.

In the drawings—

Figure 1 is a view mainly in vertical section of a fitted action body for a small bore rifle as aforesaid showing the relationship of the parts immediately preparatory to firing.

Figure 2 is a view similar to Figure 1, but showing the mechanism in the position which it assumes when the gun is fired.

Figure 3 is a vertical sectional view taken substantially on the line 3—3 of Figure 2.

Figure 4 is a vertical sectional view taken substantially on the line 4—4 of Figure 2.

In the drawings like numerals of reference indicate similar parts in the several views.

The upper part of the action body 4 is provided with a slideway 5 within which is mounted a bolt 6 which embodies a firing mechanism and an ejector mechanism of known kind the firing mechanism incorporating a firing pin 7 and a spring 8. The ejector mechanism is actuated by an ejector cam 17a, the remainder of the ejector mechanism not being shown because no other

portion thereof engages or cooperates with the cocking and firing mechanism constituting the invention.

Fulcrumed on a bush 10a mounted on a horizontal pin 10 passed through holes in the side plates 4a and arranged on the underside of the action body 4 and to the rear of the breech 11 is a lever 12 hereinafter called the cocking lever, the longer arm 12a of which is curved so as to conform to the shape of the adjacent part of the rifle butt indicated by the chain line A in Figure 1. The said longer arm 12a is in contact with the rifle butt when in the firing position, see full line position Figure 1. The shorter arm of the said 15 cocking lever 12 is forked as at 12b and the limbs of the forked section of the cocking lever 12 are provided at the upper ends with waisted ball headed portions 12c which engage within complementary slots 6a formed at each side of the 20 central portion of the bolt 6.

The slots 6a are provided at the forward end with inclined cam faces 6b for a purpose to be described hereinafter.

Also fulcrumed on the bush 10a and located between the limbs of the forked section 12b of the cocking lever 12 is a tumbler lever 13, the nose 13a whereof co-operates with the sear 14a formed at the upper end of a lever 14, herein-after called the intermediate lever 14, which is fulcrumed on a pin 14b supported in bearings carried by the side plates 4a said pin 14b passing through an elongated slot 14c in the said intermediate lever 14. The lower end of the intermediate lever 14 co-operates with a shouldered portion 15a carried by a trigger lever 15. The trigger arm 15b itself depends below the side plates 4a and is enclosed by a trigger guard 16.

Adapted to bear on the breech side of the depending and longer arm of the intermediate lever 14 adjacent to the fulcrum pin 14b is a wound spring 17 one end of which is hooked beneath the ejector cam 17a and the other end of which bears against the intermediate lever 14. A sensitive spring pressed thimble plunger 18 which is slidably mounted in a recess 15c formed in an up-standing part 15d of the trigger lever 15 bears on the opposite side of the depending and longer arm of the intermediate lever 14, adjacent the lower end thereof.

Adapted to bear on the underside of the forward end of the trigger lever 15 adjacent to the shouldered portion 15a is a spring pressed thimble plunger 19 the lower end of the spring 20 located within which is in abutment with a flange 55 on the head of a vertically arranged slidable pin

21 having a wedge faced lower end 21a which cooperates with a complementary wedge face 22a formed at one end of a horizontally disposed slideable pin 22. The other end of this pin 22 has at its opposite end also a wedge face 22b which cooperates with the taper end 23a of a vertically arranged slideable pin 23 the upper end whereof is in abutment with the lower end of an adjusting screw 24 mounted within a tapped hole in the block 16a forming part of the trigger guard 16.

The spring 18a associated with the plunger 18 and the oppositely acting spring 17 substantially balance one another but with a slight preponderance to the spring 18a so that, when free of influence of the spring 8, the spring 18a urges the intermediate lever 14 in a counterclockwise direction. By reason of the substantial balancing of the force of the springs 17 and 18a a very sensitive relationship between the sear 14a and the nose 13a of the tumbler-lever 13 is obtained. The spring 8 associated with the firing pin 7 is considerably stronger than the spring 18a and, consequently, the tumbler-lever 13 tends to urge the intermediate lever 14 in a clockwise direction.

The screw 24 in conjunction with the wedge ended pins 21, 22 and 23 admits of the adjustment of the plunger 19 so as to enable the trip resistance of the trigger arm 15b to be adjusted to suit individual requirements and to ensure that after setting the said trip resistance remains constant.

The tumbler lever 13 incorporates an upstanding waisted ball headed portion 13b which is engaged within a slot 7a in the central portion of the firing pin 7. The slot 7a is but slightly longer than the maximum dimensions of the portion 13b of the tumbler-lever, having flat transverse end walls against which the tumbler-lever head bears during cocking and firing.

A stop pin 25 is provided for determining the limit of the forward movement permitted to the lower arm of the intermediate lever 14.

Operation

When it is desired to cock the piece, the cocking lever 12 is swung in a counterclockwise direction, pivoting on the bushing 10a. Almost as soon as the lever 12 is moved the lower edge of the tumbler-lever 13 is engaged by the forward end 12a of the bottom of the gap between the arms 12b of the cocking lever. This "picks up" the tumbler-lever 13 and carries it along with the cocking lever 12. As the tumbler lever 12 is swung farther (see Figure 2) its nose 13a is withdrawn from beneath the sear 14a of the intermediate lever 14 which has gradually been sliding down the face of the nose. Because the spring 18a is somewhat stronger than the spring 17, the intermediate lever 14 continues to swing in a counterclockwise direction until its movement is stopped by engagement with the stop pin 25. As the cocking lever 12 is swung, its bifurcated arms and the tumbler lever 13 both continue to swing around the bushing 10a. The head 13b of the tumbler lever 13 presses against the rearward end of the slot 7a moving the firing pin 7 backward and compressing the spring 8. Shortly thereafter the rearmost edges of the heads 12c of the cocking lever arms engage the rear edges of their respective slots 6a in the bolt 6. Further movement of the cocking lever then moves the bolt bodily backwards withdrawing it from the breech and permitting the ejector cam 17a to engage the ejector mechanism to eject the old spent cartridge. As the bolt continues to move

backwardly the ejector mechanism is rocked slightly in a counterclockwise direction which further eases the tension on the spring 17 and allows the spring 18a to swing the intermediate lever 14 around its pivot point. As the intermediate lever 14 swings to the limit of its travel against the pin 25, its lowermost point is moved away from in front of the uppermost step of the trigger 15. The trigger spring 20 swings the trigger upwardly and inserts the portion 15a behind the intermediate lever 14.

The bolt and the lever 12 have reached the limit of their travel at approximately this time. As the lever 12 is returned to its normal position the forward side of the heads 12c engage against the forward ends of the slots in the bolt and move the bolt forwardly. Of course, a new cartridge has been inserted through the loading and ejecting opening 4b prior to returning the lever 12 to closed position. As the lever 12 continues to swing in a clockwise direction the bolt moves forward and the firing pin 7 urged by the spring 8 also moves forward. This returns the tumbler lever 13 to the position shown in Figure 1, the tumbler lever 13 being stopped by engagement between the forward face of its nose 13a and the face of the sear 14a on the intermediate lever 14. The intermediate lever 14 is thus urged in a clockwise direction which presses its lowermost point against the portion 15a of the trigger 15. This position of engagement between the tumbler lever 13 and the intermediate sear carrying lever 14 and between the lever 14 and the trigger 15 stops the clockwise rotation of the tumbler lever 13 and holds the firing pin against further forward movement. This position is reached before the lever 12 and the bolt are restored to closed position.

The lever 12 is moved the remaining distance to the position shown in the solid lines, which moves the bolt to close the breech and eventually swings the upper ends of the heads 12c of the cocking lever 12 against the cam faces 6b of the slot 6a, wedging the bolt in breech closing position.

The piece is then cocked and ready for firing. When the trigger 15b is pulled, the trigger lever 15 is swung in a clockwise direction against the force of the trigger spring 20. This removes the portion 15a from behind the lower corner of the intermediate lever 14. The only force then tending to hold the intermediate lever 14 with its sear 14a against the nose 13a of the tumbler lever 13, is the spring 18a. This spring is overcome by the force of the firing spring 8 acting against the tumbler lever 13. The intermediate lever 14 is then sharply snapped around its pivot in a clockwise direction far enough to allow passage of the nose 13a of the tumbler lever 13 past the sear 14a of the lever 14, the spring 8 providing the force for this movement and at the same time snapping the firing pin forwardly to fire the cartridge held in the breech.

After the trigger 15b is pulled into the position shown in Figure 2, and the piece has been fired as described, the marksman releases the trigger. When the pressure of his trigger finger is removed from the trigger, the spring 20 tends to urge the trigger lever 15 in a counterclockwise direction to rotate it sufficiently to clear it from engagement with the guard 16. At this time, however, the lowermost left (Figure 2) corner of the intermediate lever 14 is engaged with the upper surface of the portion 15a of the trigger lever 15 which would obstruct the restorative movement of the

trigger lever 15 except for the fact that the intermediate lever 14 has the elongated slot 14c, which allows it to move upwardly relative to the pin 14b sufficiently to permit the trigger 15b to move forwardly a slight distance.

It will be appreciated that a bolt action mechanism as hereinbefore described is simple in construction and efficient and makes for the comfort of a marksman particularly in the case where such an individual is engaged in a shooting competition.

I claim:

1. In a rifle having a slideable bolt, a firing pin slidably mounted on said bolt and a trigger, a cocking mechanism comprising, in combination, a vertically extending, angularly movable cocking lever pivotally mounted on a horizontal axis below the bolt, said cocking lever having a bifurcated upper end forming laterally spaced parallel arms, the bolt of said rifle having a pair of laterally spaced elongated grooves therein into which the upper ends of said arms extend, a pivotally mounted, angularly movable tumbler-lever extending upwardly substantially parallel to said cocking lever and engageable thereby for movement therewith during retraction of the bolt, the bolt and firing pin each having a slot through which and into which, respectively, the upper end of said tumbler lever extends, a firing spring acting between the bolt and the firing pin and urging the firing pin forwardly toward a cartridge in the breech of the rifle, and an intermediate sear lever pivotally mounted on the rifle and having a sear at its one end which is movable into the path of and slidably engageable with said tumbler lever to hold said tumbler lever and the firing pin in retracted and cocked position when the bolt is moved into closed position, the other end of said intermediate sear lever being engageable with the trigger, whereby pressure of said

10

25

30

40

firing spring against the firing pin is applied to said tumbler lever and opposed by said intermediate sear lever, and firing is effected by pressing the trigger and swinging said intermediate lever out of the path of movement of said tumbler lever.

2. A mechanism in accordance with claim 1 in which the tumbler lever is mounted co-axially with the cocking lever and located between the arms of the cocking lever.

3. A mechanism in accordance with claim 1 in which the cocking lever has means for engaging the tumbler lever only on the bolt retracting movement of the cocking lever, the tumbler lever being returned forwardly to cocked position by the force of the firing spring thereon.

4. A mechanism in accordance with claim 1 in which the axes of the cocking lever, the tumbler lever, the intermediate sear lever and the trigger are all perpendicular to the vertical plane of the center line of the bolt and the firing pin; and the tumbler lever, the intermediate lever and the trigger all move in the same direction around their pivots when the piece is fired.
